UNITED STATES PATENT OFFICE.

MAX BROWN, OF BROOKLYN, NEW YORK, ASSIGNOR TO ROYAL METAL LIGHTING FIXTURE CO., INC., A CORPORATION OF NEW YORK.

DESIGN FOR A LIGHTING-FIXTURE STRAP.

Application filed February 17, 1927. Serial No. 20,792. Term of patent 3½ years.

To all whom it may concern:

Be it known that I, MAX BROWN, a citizen of the United States, and a resident of Brooklyn, county of Kings, and State of New York, have invented a new, original, and ornamental Design for a Lighting-Fixture Strap, of which the following is a specification, reference being had to the drawing, forming a part hereof.

In these drawings:

Figure 1 is a side elevational view of the lighting fixture strap, and

Figure 2 is a diagrammatic side outline view of the same.

I claim:

The ornamental design for a lighting fixture strap substantially as shown.

MAX BROWN.
